Attorney

UNITED STATES PATENT OFFICE

FRANK S. TRUSLER, OF VERNON, TEXAS

ARTIFICIAL TOOTH

Application filed January 25, 1928. Serial No. 249,328.

This invention relates to artificial teeth and it has more particular reference to an interlocking connection between a porcelain facing and a metallic backing or mounting 5 therefor.

I am well aware of the fact that the art to which this invention relates is quite active, and that a multitude of different types of connections have been patented for facilitating mounting of porcelain facings.

It follows that, in view of my knowledge of the prior devices, I have evolved and produced what I believe to be a characteristically different kind of a connection between the facing and backing, which connection is dependable and accompanied by advantages which will be hereinafter made apparent.

My principal aim is to generally improve upon known constructions of this class, by 15 providing one which embodies features capable of being readily standardized for interchangeability, one which is perfectly sanitary, modernized, practicable in construction, and use.

Referring to the drawings now by numerals:

Figure 1 is a view in section and elevation showing the novel connection between the facing and backing.

Fig. 2 is a transverse vertical section on an enlarged scale, taken approximately upon the plane of the line 2-2 of Fig. 1.

Referring now to the drawings by reference numerals, it will be observed that the 25 metallic backing is designated by the reference character 3 and that this carries the usual gold casting 4 on its interior. The numeral 5 designates a porcelain facing which, as is understood, will vary in configuration and size, according to its predetermined position in the mouth.

In accordance with the present invention, the porcelain facing 5 is provided with a cylindrical pocket having a metal lining 6, one end portion of which projects into a counter-bore 7. Disposed concentrically in this metal-lined socket, is a fixed coupling pin 8 whose inner end is roughened or threaded as 30 at 9. Surrounding the threaded portion of

the pin is a conical ferrule or expanding collar 10.

The complementary backing plate is provided with a cylindrical casing 11 and a central coupling tube 12, which telescopically 55 receives the pin 8. The casing 11 is of a diameter to fit snugly and telescopically within the lining 6 of the socket. It will be noted that a conical expanding collar 13 surrounds the casing 11. It follows that when the 60 parts are fitted together in the telescoping relationship shown in Fig. 1, one end of the lining will be spread on the collar 13 out into the counter-bore 7, and that one end of the coupling tube 12 will be expanded or flared 65 outwardly on the conical expander 10.

The numeral 14 designates the cement filler which is placed between the tube 12 and the surrounding casing 11. Then too, I employ one or more eccentric pins 15 on the backing 70 plate, these extending in sockets in the facing to prevent relative rotation of the backing plate, and facing.

It is obvious from the foregoing, that what I have endeavored to do, is to provide a dependable connection between the porcelain facing and metallic backing in artificial tooth constructions. It is evident that the structure as herein shown and described is efficient in performance, and capable of fulfilling the 75 requirement of a device of this class.

It is economical from every standpoint, and especially suitable for practical use by dentists. It is believed, however, that persons skilled in the art to which the invention 85 relates will be able to understand and appreciate the superior features. Therefore, a more lengthy description is regarded unnecessary.

Minor changes in shape, and size, and rearrangement of details coming within the 80 field of invention claimed may be resorted to if desired.

Having thus described my invention, what I claim as new is:—

In an artificial tooth construction, a backing member, a facing associated therewith, said facing being formed in one side with a socket, a metal lining for the socket, a concentric pin mounted in said socket, a tube 100

carried by said backing member and fitting snugly and telescopically upon said pin, expanding means between the pin and free end portion of the tube, a cylindrical casing carried by said backing member, and surrounding said tube, in spaced concentric relation, said casing fitting telescopically into said socket, and being in contact with the socket lining, and expanding means interposed between said casing and the free end portion of said lining.

In testimony whereof I affix my signature.

FRANK S. TRUSLER.
